UNITED STATES PATENT OFFICE.

NICOLA GIUSTO AND CARLO DE-FELICE, OF NEW YORK, N. Y.

REPEATING FIREARM OR RIFLE.

964,419.

Specification of Letters Patent. Patented July 12, 1910.

Application filed January 28, 1910. Serial No. 540,714.

To all whom it may concern:

Be it known that we, NICOLA GIUSTO, a subject of the King of Italy, and CARLO DE-FELICE, a citizen of the United States, residents of the city of New York, county and State of New York, have invented certain new and useful Improvements in Repeating Firearms or Rifles; and we do hereby declare the following to be a full, clear, and exact description of the invention, such as will enable others skilled in the art to which it appertains to make and use the same, reference being had to the accompanying drawings, in which:—

15 Figure 1 is an elevation or side view partly sectioned, of the interior of our improved firearm, showing the hollow stock without cover, the barrel and its support being partly broken away, the said view being 20 constructed and arranged in accordance with our invention. Fig. 2 is an elevational side view of our improved firearm, showing the same stock with the cover on, and showing also the external working parts of the mechanism which will be hereinafter described.

25 Fig. 3 is a fragmentary sectional view showing the way of guiding the conveying chain and the cartridges in the interior of the stock and Fig. 4 is an elevational side view of the same, the cover having been removed. Fig. 30 5 is a fragmentary elevational side view, partly sectioned, showing an improved rotating cylinder and an improved barrel support which can be used in connection with 35 our firearm, and Fig. 6 is an elevational front view partly sectioned of said cylinder.

This invention relates to improvements in firearms or rifles and particularly to automatic or semi-automatic guns, and has for 40 an object a convenient disposition of parts by which the weight of the gun can be easily supported in every position.

Another object of the invention is to provide means for lessening the shocks effected 45 by the recoil against the shoulder, this being quite an inconvenience, especially in quick firing.

A further object of the invention is the arrangement in a gun of an automatic discharge mechanism, a magazine and means 50 for conveying cartridges to the automatic discharge mechanism.

With these and other objects in view the invention comprises certain other novel combinations, constructions and arrangement of

parts as will be hereinafter fully described and claimed.

We have found that an objectionable feature of guns of the usual design is the fact that these must be held pressed against the shoulder, the weight of the gun resting entirely on the arms, and requiring the use of both arms in the firing.

A detail of our invention, which can be applied to guns of any description, consists 65 in providing means for supporting the weight of the gun partly on the shoulder and partly on one arm, moreover, by actually making an arm-hole in the body of the gun this can be carried on the shoulder 70 in any position, and can be quickly passed from the position of rest to the firing position by rotating it around the shoulder; this arrangement also renders possible the firing 75 of the gun with the use of a single arm when necessary.

In order that the invention may be more clearly understood, an embodiment of the same is shown in the accompanying drawings in which: 1 is a hollow stock, preferably of metal, of a suitable size and form of construction, 2 is a cover for the same, 3 is a barrel and cylinder holder made of tough steel or of any other suitable material, rigidly connected with the stock, and 4 is a 85 common rifle barrel fitted to part 3. An arm hole 5 is provided which could obviously be made solid, cast in the stock, but which in the drawings is shown as formed partly by the stock and partly by a swinging arm 6 90 and by a strap 7.

Part 6 swings around the fulcrum pin 8, and is fixed in the desired position by the bolt 9, running through the slot 20, the object of this arrangement being the making of 95 an opening adjustable to arms of any size. The strap 7, preferably of leather, is rigidly connected to the stock at one end, while at the other end it engages a hook 10 or is held in any other convenient way which will permit its quick release: this will be found convenient to do when the gun has to be fired lying with the body flat on the ground.

11 is a magazine in which the cartridges are kept horizontally in a column or in several columns side by side, suitable arrangements (not shown) being provided for their proper feeding to the conveyer 12. Arrangements will also be provided to prevent the cartridges from assuming a different po- 110

sition when the gun is not held horizontally, by exercising a pressure on their sides or on their ends or by any other suitable means (not shown).

5 In the drawings the magazine is shown as consisting of a single column of cartridges, these being fed to the conveyer by gravity. The conveyer is constituted by a chain belt 12, provided at even spaces with projections 13, which push the cartridges while traveling to the feeding mechanism, and also separate one cartridge from another: this will prevent any danger of the bullet of a cartridge coming in contact with the rear of the preceding cartridge. This conveyer is provided with rollers 14 which run in grooves cut in the stock 1 and on the inside face of the cover 2 thus avoiding any friction of the cartridges against the upper surface of the chamber 15. Other advantages of this arrangement are that the chain may be made to travel along an irregular line, clearing the arm hole, and that the chain is supported all along the way, the weight of the cartridges not being borne entirely by the sprocket wheels 16 and 17. The sprocket wheel 16 runs idle on the shaft 18, while the sprocket wheel 17 is rigidly fixed on the shaft 19.

30 21 is a movable part provided with two prongs 22 and which acts as a shock absorber. The prongs 22 are bored along their entire length to receive pins 23 rigidly fixed to the stock 1, and which act as guides for the longitudinal motion of part 21. Pins 23 have an enlarged head to which corresponds an enlarged part of the hole in prongs 22, and which acts as a stop for the part 21 against the action of springs 24.

46 When the gun is fired, the recoil causes a pressure of part 21 against the shoulder, and springs 24 giving way, part 21 will move onward until the effect of the shock will have been absorbed. In the particular gun shown in the drawings, the motion of part 21 is utilized as prime mover for the other mechanisms of the gun as will be hereafter described; but it is obvious that in cases where the force of the impact should not be

50 sufficient, the action of part 21 will be limited to that of a shock absorber, while a spring motor (not shown), or a hand lever 25 with convenient means for regulating its stroke, will be partly or totally used for causing the feeding and discharging mechanisms to act. Owing to this particular use, part 21 is provided with two regulating screws 26, which by a proper adjustment, and by limiting the stroke onward of part 60 21 to the point when said screws 26 come against the heads of pins 23, will give a means for lengthening or shortening the stroke of other parts whose motions are dependent from it.

65 Rigidly connected with part 21 is a rack

27, whose object is to impart the motion received by part 21 upon the firing of a shot, and against the action of springs 24, to a pinion 28, keyed on a shaft 29. On this same shaft 29 are keyed on two opposite sides of the gun two levers 30, 31, carrying the spring pawls 32, 33, and the springs 32', 33'. On the onward stroke of part 21, rack 27 will cause pinion 28 and shaft 29 to rotate from left to right, causing pawl 33 on lever 31 to engage in the teeth of the internally toothed crown of a sprocket wheel 34, which turns loose on the same shaft, and producing the rotation of this wheel 34: the angle of the rotation being regulated by the stroke of rack 27 and consequently by a proper adjustment of the screws 26. Sprocket wheel 34 is connected with a chain belt 35 to another sprocket wheel 36 keyed on shaft 19, and causes the rotation of this shaft and consequently of the internal sprocket wheel 17 and the forward motion of the conveyer 12.

The stroke of the conveyer will be so regulated as to be of the same exact length as the intervals in between the projections 13, so that at each stroke the conveyer will push the cartridge shown in the position 37 forward and into the receptacle 38 of the rotating cylinder 39, moving at the same time all the cartridges one space, and remaining at the end of the stroke with an empty space right under the magazine. Into this empty space a new cartridge will automatically be placed, by gravity or by any other means, as stated before.

40 is a spring attached at one end to the part 3, and its object is to guide without shock the cartridge 37 into its proper position. The cartridge chamber 15 is so shaped at this stage of the cartridge travel as to allow of its gradual change of direction for entering the receptacle 38.

Upon the completion of the onward stroke of part 21 and of the mechanisms hereinbefore described, springs 24, with the aid of some other motive power if necessary, a spring motor, or a hand lever or the like, will cause part 21 to go back to its former position: rack 27, pinion 28 and shaft 29 will consequently also go in the opposite direction, causing at this time pawl 32 on lever 30 to engage in the teeth of the internally toothed crown of a sprocket wheel 41, and causing said sprocket wheel to rotate from right to left. Sprocket wheel 41 is connected with the chain belt 42 to another sprocket wheel 43, keyed on the eccentric shaft 44: and parts will be so arranged as to cause during the return stroke of part 21, an entire revolution of the eccentric shaft 44, and not more nor less. During said revolution a breech-block which for convenience of construction is shown as composed of two parts 45, 46, will be moved back by the ec-

centric, to which it is connected by link 47 swinging on pin 48, during the first half, and returned to its former position during the second half of the revolution of said eccentric shaft 44.

49 is a hammer or firing pin, and is shown in the drawings in the position ready for shooting. 50 is an enlarged part of said hammer, which rests against a spring 51, and 52 is a notch which engages in the hook of a crank lever 53. By pulling the trigger 54, link 55 causes crank lever 53 to disengage notch 52, and spring 51, acting against part 50 of the hammer will cause its firing 15 the cartridge 56. When breech-block 45—46, in the manner hereinbefore described is caused to retract from the position shown in the drawings by the first half of the revolution of eccentric shaft 44, hammer 49 is 20 caused to follow and to return to its former position, notch 52 reengaging the hook in the crank lever 53.

57 is a safety stop for the lever 53, pivoted on a shaft 57': by turning it 90 degrees to the right from the position shown in the drawing, by means of the button 58, its top part will go against the lower arm of crank lever 53, preventing this from disengaging notch 52, or in other words giving a 30 position of safety to the firearm.

39 is a rotating cylinder made of steel or of any other convenient material, rotating on pin 59, and is provided with several chambers adapted to receive the cartridges 35 to be used in the gun, and provided at one end with an equal number of notches, as seen in the usual type of cylinder used in revolvers. In Figs. 5 and 6 this cylinder is shown as composed of two parts, 39' and 40 39'', and this construction is suggested in preference to that shown in Fig. 1 as it adds to the lightness of the piece and it facilitates its cooling. Part 39'' is provided with ribs 61 of a shape adapted to fit the internal 45 opening of part 39', and is provided with holes 62 through said ribs with the object of further improving the cooling of the piece. Said cylinder 39 carries the cartridges received from the conveyer in the 50 position 38 to the firing position 56, by turning on pin 59 of one step at each shot. This turning action may be caused in a manner similar to that used in revolvers, or in any other convenient way; in the drawings this 55 action is performed during the first part of the stroke of the breech-block 45—46 by means of a link 63 connected to it and to a crank lever 64 bearing a pawl shown in Fig. 1 in dotted lines. This pawl will begin to 60 engage notch 60 when the breech-block has retired enough to clear the cartridge chamber 56 and to allow the turning of the cylinder.

Conveyer 12 will accompany the cartridges in the position 38 only to a certain

point, a space having to be provided for the turning of the projections 13 around the sprocket wheel 17; an inclined plane 65 is therefore provided which will gradually push the cartridges all the way inside of 70 the chambers, during the turning of the cylinder from the position 38 to the position 56.

Proper means (not shown) in the way of antagonistic toothed wheels and pawls, or frictional brakes such as used in presses, 75 and the like, will be provided to prevent cylinder 39, shaft 19 and shaft 44 to turn only in their proper direction.

The hollow stock 1 is provided with lugs 66 tapped and adapted to receive the screws 67 which fasten the cover 2 to the stock. The magazine 11 is protected by a cover 68. After the cartridge 56 has been fired the cylinder 39 turns one step, presenting a new cartridge to the action of the firing pin, 85 while the empty shell has to be ejected before the chamber reaches the position 38. Many different means could be devised to this object without departing from the spirit of this invention, and one is shown in Fig. 2. 90 A gear 69 is keyed on the shaft 29 and rotates with it, causing another gear 70, turning loosely on a pin 71, to rotate in a different direction. This gear 70 engages a rack 72 running through two bearings 73, and bearing an extractor 74 of a shape adapted to catch the rear part of a shell. When part 21 moves forward, and shaft 29 rotates from left to right, the rack 72 moves backward, drawing the empty shell previously 100 engaged by extractor 74 from its chamber, when the shell will be well out of said chamber it will at a certain point knock against a notch (not shown) which prevents any further backward travel of the shell while the 105 extractor continues for a while in the same direction. This causes the cartridges to be forced out of the extractor and to be expelled, this action being in other words similar to that of the ejector used in many well-known types of guns. 110

Upon part 21 beginning its return stroke, rack 72 will be driven to its former position, and the extractor 74 will engage the next empty shell. The hand lever 25 will be used 115 for causing the motion of the various parts in the same way as described, to bring the first cartridge into firing position, or while unloading the gun, stop 57 having been previously turned to the safety position. This 120 hand lever, as said before, may also constitute the motive power used in the operation of the gun when firing, should part 21 be used only as a shock absorber. The stock 1 is provided at its forward end with 125 a nose 75, which by being connected by pin 76 to a projection 77 of part 3, reinforces the system.

Other details of our invention which may be used in connection with any type of gun 130

are shown in a trigger guard 79, and in a special barrel support 80.

A projection 78 from the stock and the trigger guard 79 are shaped so as to afford 5 a good grip to the hand, the trigger guard being provided with cells adapted to receive the middle finger at the front, the ring finger against its lower face, and the thumb on and against its rear face.—Part 80 is 10 a bracket preferably of hollow metal, covered with leather or felt 81, connected at one end to the stock by the pin 76, and at the other end supporting the barrel at about the middle of its length; an asbestos packing 82 prevents the heat from the barrel 15 from being communicated to the bracket 80, and while this offers a very convenient grip for the left hand while firing it has the further advantage of leaving the barrel entirely exposed to the air for its entire 20 length, so that its cooling will be much improved.

It is to be noted that the mechanisms described for discharging the cartridges can 25 be in some instances much simplified, doing away with the breech-block and firing pin and substituting for it a device similar to that used in revolvers; the way of operating said breech-block and firing pin when used 30 could also be modified. These and various other modifications and changes may be made in the details of construction without departing from the spirit of the invention, therefore we do not wish to confine ourselves 35 to that shown and described.

Having thus described our invention, what we claim as new, and desire to secure by Letters Patent is:

1. In a firearm or rifle, in combination 40 with a barrel and suitable firing mechanism, a stock provided with a hole adapted to receive the arm and a magazine behind the shoulder, holding one or more columns of cartridges in a longitudinal position.

45 2. In a firearm or rifle in combination with a barrel and suitable firing mechanism, a hollow stock provided with an opening adapted to receive the arm, a magazine behind the shoulder, a rotating cylinder, means 50 for feeding the cartridges through the hollow stock to the rotating cylinder, and means for rotating the cylinder.

55 3. In a firearm or rifle in combination with a barrel, a hollow stock provided with an opening adapted to receive the arm, a magazine behind the shoulder, a rotating cylinder, means for feeding the cartridges through the hollow stock to the rotating cylinder, means for rotating the cylinder, 60 means for discharging said cartridges, and an extractor for extracting empty shells.

65 4. In a device of the character described, a hollow stock provided with an opening adapted to receive the arm, a magazine behind the shoulder, means for absorbing the

shock due to recoil while firing, a rotating cylinder, means for feeding the cartridges through the hollow stock to the rotating cylinder, and means for rotating the cylinder.

70 5. In a device of the character described, a hollow stock provided with an opening adapted to receive the arm, a magazine behind the shoulder, a rotating cylinder, means for absorbing the shock due to recoil while firing, means for feeding the cartridges through the hollow stock to the rotating cylinder, means for rotating the cylinder, means for discharging said cartridges, and an extractor for extracting empty shells. 80

85 6. In a device of the character described, a hollow stock provided with an opening adapted to receive the arm, a magazine behind the shoulder, means for absorbing the shock due to recoil while firing, means for utilizing the force thus obtained for the operation of the gun, a rotating cylinder, means for feeding the cartridges through the hollow stock to the rotating cylinder, means for rotating the cylinder, means for discharging said cartridges, and an extractor for extracting empty shells. 90

95 7. In a device of the character described a hollow stock, an arm receiving member, a magazine at the rear end, means for absorbing the shock due to recoil while firing, separate means for the operation of the gun, a rotating cylinder, means for feeding the cartridges through the hollow stock to the rotating cylinder, means for rotating the cylinder, means for discharging said cartridges, an extractor for extracting empty shells, a trigger guard provided with cells 100 adapted to receive the middle finger in front, the ring finger against its lower face and 105 the thumb on and against its rear face, and means for supporting the gun at its outer end leaving a free circulation of air around the barrel.

110 8. In a device of the character described a hollow stock, an arm receiving member, a magazine at the rear end, a longitudinally moving shoulder piece, pins for guiding said motion, springs opposing said motion, means for adjusting the stroke of said moving part, means for utilizing said motion for the operation of the gun, a rotating cylinder, a conveyer for conveying the cartridges through the hollow stock to the rotating cylinder, means for rotating the cylinder, a breech-block, a firing pin, means for operating said breech block and firing pin, and an extractor for extracting empty shells. 115

120 9. In a device of the character described a hollow stock, an arm receiving member, a magazine at the rear end, a longitudinally moving side piece, pins for guiding said motion, springs opposing said motion, means for adjusting the stroke of said moving part, means for utilizing said motion for 125 130

- the operation of the gun, separate means for operating the gun independently from it, a rotating cylinder, a conveyer for conveying the cartridges through the hollow stock to the rotating cylinder, means for rotating the cylinder, a breech-block, a firing pin, means for operating said breech-block and firing pin, and an extractor for extracting empty shells.
- 10 10. In a device of the character described a hollow stock, an arm receiving member, a magazine at the rear end, a longitudinally moving shoulder piece, pins for guiding said motion, springs opposing said motion, means for adjusting the stroke of said moving part, means for utilizing said motion for the operation of the gun, separate means for operating the gun independently from it, a rotating cylinder, means for rotating the cylinder, a conveyer for conveying the cartridges through the hollow stock to the rotating cylinder, a breech-block, a firing pin, means for operating said breech-block and firing pin, an extractor for extracting empty shells, a trigger guard provided with cells
- 15
- 20
- 25
- adapted to receive the middle finger in front, the ring finger against its lower face, and the thumb on and against its rear face, and means for supporting the gun at its outer end leaving a free circulation of air around the barrel.
11. In a device of the character described a hollow stock, an arm receiving member, a magazine at the rear end, a longitudinally moving shoulder piece, pins for guiding said motion, springs opposing said motion, means for adjusting the stroke of said moving part, separate means for the operation of the gun, a rotating cylinder, means for rotating the cylinder, a conveyer for conveying the cartridges through the hollow stock to the rotating cylinder, a breech-block, a firing pin, means for operating said breech-block and firing pin, and an extractor for extracting empty shells.
